(57) **CLAIM**

The ornamental design for an inflator, as shown and described.

DESCRIPTION

FIG. 1 is a front perspective view of an inflator embodying the ornamental design of the present invention.

FIG. 2 is a rear perspective view thereof.

FIG. 3 is a front plan view thereof.

FIG. 4 is a rear plan view thereof.

FIG. 5 is a side view thereof.

FIG. 6 is an opposite side thereof.

FIG. 7 is a top view thereof; and,

FIG. 8 is a bottom view thereof.

The broken lines in FIGS. 1-8 are for illustrative purposes only and form no part of the claimed design.
